UNITED STATES PATENT OFFICE.

OLAF HALVERSON, OF WARREN, MINNESOTA.

CALENDAR.

Application filed April 2, 1927. Serial No. 180,463.

My invention relates to calendars, and has for an object thereof to provide a calendar adapted to be embodied within the structure of a writing instrument and, particularly, within the cap of a fountain pen.

Another object of the invention resides in forming said calendar so as to include all of the months of a year.

A still further object of the invention resides in employing a portion of a fountain pen cap as a drum or holder for the reception of a table comprising a rolled sheet having imprinted thereon the dates of the various months, and in providing a sleeve or sheath encircling the table and having a window therein, said sleeve being adapted to be rotated with respect to the table on the holder to expose the different dates on the outer surface of said table.

A feature of the invention resides in printing the months of a year successively in columnar formation on a long sheet and in rolling said sheet into tubular form with the dates of one or more months exposed on the outer surface of the roll and in gumming the edges of the rolled sheet to retain the same in cylindrical form.

A further feature resides in dividing said table into sections by means of perforations extending across the same between the monthly demarcations thereon so as to permit of detaching the used sections and exposing the unused sections in the course of the year.

With the foregoing and other objects in view, which will appear in the following description, the invention resides in the novel combination and arrangement of parts and in the details of construction hereinafter described and claimed.

In the drawings:

Fig. 1 is a perspective view of a fountain pen in which a form of my invention is embodied.

Fig. 2 is an enlarged longitudinal sectional view of the cap and a portion of the barrel illustrated in Fig. 1.

Fig. 3 is a detail perspective view on an enlarged scale of the table detached from its holder in the cap of the fountain pen and illustrating one of the sections of the table partly extended from the roll.

In using a fountain pen for writing checks, as well as for numerous other purposes, it frequently becomes desirable to as-

certain a particular date in the current month. My invention meets such need by associating a table with the cap of the pen in such a manner that appropriate portions of the same may be displayed to indicate the dates of the month desired.

For illustrating the application of the invention, I have shown in Figs. 1 and 2 a fountain pen A comprising the usual barrel 10, pen point 11 and feed member 12. The barrel 10 is conventionally threaded at 13 to receive a cap 14 which, adapted to my particular invention, preferably departs somewhat from the conventional form of cap. This cap is internally threaded at 15, as usual, to screw upon the threaded portion 13 of barrel 10 and is bored in the customary manner with a tapered bore 16 adapted to fit snugly upon the tapered end 17 of the barrel when the pen point 11 is exposed for writing. The interior bore 17 of cap 14 is reduced near its outer end at 18 to form the customary shoulder 19 adapted to abut against the end 20 of barrel 10, whereby the compartment containing the pen point, when in disuse, is rendered air tight. The usual vent holes 21 may be drilled in the cap between the shoulder 19 and the threads 15.

As will be noted in Fig. 2, the end of the cap 14 is reduced in diameter exteriorly to resolve said end of the cap into a drum-like holder 22 for the tubular table presently to be described and to provide a shoulder 23. The tip of the cap is formed with an axially disposed lug 24 which is externally threaded at 25 to receive a nut or retainer 26 of substantially the same diameter as the cap proper. This lug 24 is of less diameter than the drum 22 providing a shoulder 27, which, in conjunction with the retainer 26 serves to clamp the ring portion 28 of a clasp 29 in place upon the end of the cap. This clasp is of ordinary construction and is provided with a ball 30 at the end of the same for holding the pen in the pocket of the wearer's clothing.

About the drum 22 is mounted a revolute sleeve 32 which has a bore somewhat larger in diameter than the exterior diameter of the said drum for the purpose of providing an annular space for the table bearing demarcations thereon representing the dates of the months. This sleeve is journaled at its inner end upon a flange 33 formed on the 110

drum 22 adjacent shoulder 23. The other end of said sleeve 32 is formed with an inwardly extending flange 34 which fits upon the end of said drum, the said flanges 33 and 34 serving to hold the sleeve in spaced concentric relation relative to said drum. Sleeve 32 is of such a length that the top thereof falls below the ring-like portion 28 of the clasp 29 and is held immovable longitudinally by means of the shoulder 23 and said ring-like portion, while the same may be freely rotated upon the drum 22.

In conjunction with the drum 22 I employ a printed table indicated in its entirety at B. This table is formed from a long strip of paper having printed thereon, in columnar formation, demarcations 35 indicating the dates, days, and months of the year, the months being arranged successively along the strip and the dates extending transversely across the strip. Between each monthly division the sheet is perforated along a transverse line 36 to divide the same into a number of sections 37. In preparing the table for application to the cap 14, the sheet is wound or rolled upon a suitable cylindrical mandrel starting with the last month of the year with the printing thereon on the outer face of the sheet. While so rolled, the edges of the sheet are gummed with a suitable adhesive, so that the sheet when removed from the mandrel forms a roll capable of being slipped over the drum 22 and against the shoulder formed by the flange 33. Said drum may be slightly tapered so that as the rolled table B is applied to the drum, it becomes snugly wedged thereon.

The sleeve 32 is formed with a longitudinal slot 37 which extends transversely of the strip of paper from which the table B is made, said slot forming as a window in said sleeve, through which a single row of dates upon the table B may be viewed at each setting of said sleeve. Upon rotating the sleeve 32 relative to the drum 22, successive rows of dates may be exposed enabling the user to view any of the dates on the outer surface of the table B. If desired, the table B may be constructed with two months visible at one time upon the exterior of the roll so that both the instant and the preceding month may be viewed. At the end of each month the last section of the roll is torn off along a line 36 to expose another month, thereby making the table serve for an entire year.

The invention is highly advantageous in that it provides a simple and convenient calendar in association with the cap of a fountain pen. The calendar can be incorporated in the pen without materially altering any important portion thereof and without changing the appearance or disfiguring the pen in any manner. By ar-

ranging the slot in such a manner as to expose a single row of dates at one time, the calendar can be used for keeping account of the current week, thereby greatly expediting the determination of the instant date or any date within the instant week. A table for an entire year may be positioned within the cap at a single filling so that the subsequent months will at all times be available as with the ordinary calendar, giving the device the maximum degree of utility. The incorporation of the calendar with the cap does not in any way interfere with the use of the cap in conjunction with the pen proper, nor interfere with the manipulation of the pen by the writer.

Changes in the specific form of my invention, as herein disclosed, may be made within the scope of what is claimed without departing from the spirit of my invention.

Having described my invention, what I claim as new and desire to protect by Letters Patent is:

1. In combination, the cap of a fountain pen having a portion thereof forming a drum-like holder, a tubular table fitting the holder, said holder having a shoulder adjacent one end thereof, a sleeve revoluble upon said holder and abutting at one end against said shoulder, said sleeve having a window adapted to be registered with portions of said table, and a retainer secured to the other end of said holder to keep said sleeve in position on the holder.

2. In combination with the cap of a fountain pen having a drum-like portion at one end thereof of diameter less than said cap proper to form a shoulder, of a table encircling said drum-like portion, a sleeve revoluble upon said portion and abutting at one end against said shoulder, said sleeve having a window therein for registration with a portion of said table, and a retainer fitted to said drum-like portion forming a second shoulder for engagement with the other end of said sleeve to hold the same against longitudinal movement with respect to said drum-like portion.

3. In combination with a cap of a fountain pen having a tubular portion adapted to form a chamber to receive a fountain pen point, said tubular member being of a diameter less than the diameter of the cap proper, a table encircling said tubular member and a sleeve revoluble upon said tubular member and having a window adapted to register with portions of said table.

4. In combination with a cap of a fountain pen having a drum-like portion at one end thereof of a diameter less than said cap proper to form a shoulder, a flange formed on said drum-like portion adjacent said shoulder, a sleeve revoluble upon said flange and spaced from said drum-like portion, a flange formed on the sleeve at its

opposite end adapted to ride upon said drum-like portion and provide an annular space between said sleeve and drum-like portion, a table disposed within said space, said sleeve having a window therein registering with a portion of said table, a lug extending outwardly from said drum-like portion at

one end thereof, and a retainer threaded upon said lug and forming a stop for depriving said sleeve of longitudinal movement. 10

In testimony whereof, I have signed my name to this specification.

OLAF HALVERSON.
